E. FRANCO

PASTRY SHELL

Filed Dec. 11, 1922

FIG. 1.

FIG. 2.

Ernest Franco

INVENTOR

BY Victor J. Evans

ATTORNEY

Geo. Babis Jr.
WITNESS:

UNITED STATES PATENT OFFICE.

ERNEST FRANCO, OF PHILADELPHIA, PENNSYLVANIA.

DESIGN FOR A PASTRY SHELL.

Application filed December 11, 1922. Serial No. 4,564. Term of patent 7 years.

To all whom it may concern:

Be it known that I, ERNEST FRANCO, a citizen of the United States of America, residing at Philadelphia, in the county of Philadelphia and State of Pennsylvania, have invented a new, original, and ornamental Design for a Pastry Shell, of which the following is a specification, reference being had to the accompanying drawing, forming part thereof.

In the drawing:—

I claim:

The ornamental design for a pastry shell as shown.

ERNEST FRANCO.
